UNITED STATES PATENT OFFICE.

CHARLES W. ISRAEL, OF PARIS, ILLINOIS.

RAILWAY-TIE.

1,099,179.

Specification of Letters Patent.

Patented June 9, 1914.

Application filed March 7, 1914. Serial No. 823,253.

To all whom it may concern:

Be it known that I, CHARLES W. ISRAEL, a citizen of the United States, residing at Paris, in the county of Edgar and State of Illinois, have invented a new and useful Railway-Tie; and I do hereby declare the following to be a full, clear, and exact description of the invention, such as will enable others skilled in the art to which it appertains to make and use the same.

The invention relates to a new and useful improved cement or composite sectional railway tie.

The aim of the invention is to provide a simple and cheap construction of tie, which, while being constructed of metal and plastic material, will be sufficiently resilient to permit certain amount of bending or yielding, as the rolling stock passes thereover, and at the same time resume its former shape when the pressure of the rolling stock is relieved.

Another object of the invention is the provision of a tie which is substantial and has a maximum durability, and can be repaired or replaced at a comparatively low expense, and furthermore the tie may be made of old scrap rails incased in plastic material or cement or the like.

Further, the invention contemplates a tie of such a construction that the rails cannot injure or cut into the top thereof, and also affording a tie of which the bolts or fastenings cannot be sheared or cut by the motion of the rails, as in the case of spikes in wood ties, thus largely lessening the liability of the spreading of rails incident to accidents.

In practical fields the details of construction may be subjected to alterations, falling within the scope of what is claimed.

The invention comprises further features and combination of parts, as hereinafter set forth, shown in the drawings and claimed.

In the drawings: Figure 1 is a plan view of the improved tie constructed in accordance with the invention. Fig. 2 is a view in side elevation and partly in section of the tie. Fig. 3 is a cross sectional view on line 3—3 of Fig. 2.

Referring more especially to the drawings, 1 and 2 designates the two sections of the tie. Each section includes a portion of an old scrap rail 3, which is inverted. This inverted rail section is surrounded by a wall or sheath of heavy wire netting or ex-

pandible metal 4, there being a space 5 intermediate the wire netting or metal as shown. Passing through apertures 6 of the inverted rail section are iron rods or bolts of sufficient length, designated by the numeral 7 having hooks on their ends, which hook or engage the netting or retaining wall, as shown at 9.

The hooks are designated by the numerals 10.

The entire inner cavity or space 5, and surrounding the outer portion of the retaining wall or netting is provided with a body of cement or other plastic material including cracked stone or gravel and the like, said body of cement and stone is marked 11 on the drawings, and by this body of cement the longitudinal core member (which consists of the inverted scrap rails), the retaining wall or netting and the rods are firmly and rigidly incorporated together, which affords a tie of weight and great rigidity. A connecting spring plate 12 which may be galvanized or otherwise treated to prevent rusting or oxidation is riveted, bolted or otherwise secured to the adjacent end of the inverted bases 13 of said rail sections 3, as shown at 14. In this manner the tie sections have stability owing to the plate 12, that is, with relation to each other, yet the plate 12 is sufficiently resilient to permit the sections of the tie to yield incident to the pressure of the rolling stock, and relative to one another. The inverted bases of the rail sections afford a broad bearing surface for the rails, the cement or concrete being arranged below said bases, enveloping or encompassing the web and the tread of the rail section, which afford a substantial core for the tie.

As shown, the rails 15 which are engaged by the rolling stock or car wheels, are disposed transversely of the tie sections upon the inverted bases 13 and adjacent the outer ends of said tie section, there being cushioning or shock absorbing means interposed between the rails 15 and the tie. This cushioning or shock absorbing means is designated by the numeral 16 and is constructed of cotton, wool or linen fabric, so treated and compressed, that a maximum durability is attained, so as to reduce and withstand the pressure of the rolling stock to a minimum. This cushioning or shock absorbing means is designed to be rolled or hammered until it becomes practically hard as

wood, so that if exposed to the summer heat, it will become pliable and elastic as a piece of rubber belting, but which is non-absorbent, and will not expand by virtue of the heat and moisture, or contract owing to the cold, and at the same time will cost but a trifle. A tie of this character when once installed in the road bed will reduce the cost of replacing, which is one of the biggest items in the maintenance of a railway. Furthermore, a tie of this character, in case it is broken or injured through accident, is not a total loss as in the case of wood ties, but can be repaired at a small cost and made as good as it was originally.

The inverted bases of the rail sections of the tie sections are provided with slots 18. One end of each slot is provided with an enlargement 19. At the time of the construction 20 the tie bolts are arranged in the ends of the narrow or contracted portions of said slots, said bolts 21 having their shanks extending upwardly, passing through the rail retaining plates or clamps 22, there being lugs 23 forming integral parts of said rail plates, and which engage the enlarged portions 19 of said slots, thereby holding the plates 22 against displacement, which plates engage the bases of the rails 15 to retain them in position.

From the foregoing it is apparent, there has been devised a simple and practical railway cement or concrete tie, and one which has been found desirable, particularly owing 35 to the many advantages and the serviceability of the same.

The invention having been set forth, what is claimed as new and useful is:—

1. A railway tie comprising a pair of concrete tie sections, each including an inverted scrap rail section constituting a core, and a spring plate connecting the two tie sections.

2. A railway tie comprising a pair of concrete tie sections, each including an inverted scrap rail section constituting a core, and a spring plate connecting the two tie sections, each inverted rail section having its inverted base provided with slots having enlarged

ends and designed to receive rail fastening means.

3. A railway tie comprising a pair of concrete tie sections, each including an inverted scrap rail section constituting a core, and a spring plate connecting the two tie sections, each tie section having a netting bonding 55 embedded in the concrete and spaced apart from the inverted rail section, and transversely disposed rods passing through the web of the inverted rail section and bonding the opposite sides of the netting.

4. A railway tie comprising a pair of concrete tie sections, means connecting said sections, each section including an inverted rail section constituting a core, each section having a bonding of netting embedded in the 65 concrete and spaced apart from the inverted rail section, and transversely disposed connecting members passing through the web of the inverted rail section and bonding the opposite side of the netting.

5. In combination with a railway tie having a body of concrete and an inverted rail section embedded therein constituting a core, the inverted base of the rail section having elongated slots, each slot having a narrow 75 portion at one end and an enlarged portion at the other, a rail fastening plate having a lug entering said enlarged portion of the slot, and fastening means passing through the narrow portion of the slot and the fastening plate for holding the plate in position, and cushioning means for the railway rail.

6. A railway tie comprising a pair of concrete tie sections, each including an inverted 85 scrap rail section constituting a core, and a spring plate connecting the two tie sections, rail fastening means on the tie, and cushioning means for the railway rail.

In testimony whereof I have signed my 90 name to this specification in the presence of two subscribing witnesses.

CHARLES W. ISRAEL.
